UNITED STATES PATENT OFFICE.

JOHN B. SOUZA, OF VALLEJO, CALIFORNIA.

DICE GAME.

Application filed July 3, 1922. Serial No. 572,650.

To all whom it may concern:

Be it known that I, JOHN B. SOUZA, a citizen of the United States, residing at Vallejo, in the county of Solano and State of California, have invented certain new and useful Improvements in Dice Games, of which the following is a specification.

My invention relates to a game simulating poker and the object of the invention is to use dice of a special design instead of cards to play the game.

The dice are accordingly similar in coloring and marking but the arrangement thereof differs between the separate cubes so that the same marking which preferably consists of characters does not appear on the same colored field in more than one of the dice.

In the accompanying drawing one embodiment of the invention is illustrated.

Figure 1 is a perspective view of one set of dice required for the game;

Figure 2 represents the cubes developed, that is to say, with their sides spread out.

Three cubes are required for the game denoted by the reference numerals 15, 16 and 17 respectively. The cubes are colored red, white, and blue in such a manner that two opposite sides of each cube, as at 18 and 19, of cube 15 are colored red. Another pair 20 and 21 are colored blue and the third pair 22 and 23 are colored white. In the other two cubes 16 and 17, the sides 24, 25 and 26, 27, respectively, are colored red and another pair of sides 28, 29 and 30, 31, respectively, are colored blue and the third pair of sides 32, 33 and 34, 35 are colored white.

Each side of each cube carries a different index or character representing the suit in playing cards. In the drawing is illustrated the characters A, K, Q, J, 10 and 9, which represent ace, king, queen, jack, 10 and 9 in a suit. The letters are also colored differently so that, for instance, the character A is colored blue and denoted by the reference numeral 36 and placed on the red field of side 18 in cube 15, while the same character denoted by 37 is colored red and placed on a white field 32 in cube 16 and the third character, denoted by the numeral 38 is white and placed on a blue field 31 in the third cube 17. Similarly all the other characters are colored red, white and blue and each one placed on a field differing in color from itself.

It should also be noted that the arrangement in each cube of the characters in relation to each other independent of color is the same so that, for instance, letters A and J of one color are placed on the opposite fields on the same cube which are colored differently from the particular characters. Opposite letter K, number 9 is placed and opposite Q, the number 10 is placed and this order is best seen in Figure 2.

It will now be noted that, when the dice are thrown and if three similar indices are exposed on the three dice, those indices will all be of different color and on a differently colored field. In this manner different suits in a card game will be represented. If, for instance, red letters on white ground represent a diamond suit in a deck of cards, and the letters A, K, and Q are on top when the dice are thrown, this will then represent a "royal flush" in this modified game. In the same manner, other hands similar to poker may be obtained as occurring in the poker game, played with ordinary playing cards and accordingly this particular game would be simulated by the use of the dice.

It will be evident that instead of using different colors, different shading or ornamentation of the sides of the cubes may be used, the opposite sides on each cube, however, being marked in the same manner. Similarly instead of using characters, the configuration of cards on the sides of the cubes may be used and the scope of the invention is intended to cover these differences of the dice. Instead of having differently colored characters, they may all have one color and placed on differently colored fields, or the sides of the cubes may all be colored alike carrying letters of different color and representing suits in a card game.

When playing a poker game with these dice, they may either be thrown from the hand or else from a cup or container or in any other suitable manner.

It is evident that the exact rules of a poker game cannot be followed when playing this dice game as there are only three suits or colors, each ranging from the ace to the 9, but that some modified rules have to be employed, which, however, are based on actual poker.

Instead of the cards being dealt by one

of the players, as in real poker, each man in this case is his own dealer, so to speak, each throw of the dice representing a deal and the showing on the dice representing the 5 player's hand, which is always exposed.

As it may happen that one or more of the dice, when thrown by a player, show the same indices as those obtained by a previous player, the rule under these circumstances 10 would be that this throw must be annulled and the throws repeated until the player obtains a deal different from all the other players.

Three card suits are represented by red, 15 white, and blue colors respectively. These three suits are divided up between the three dice so that two indicia from each suit are marked on each of the dice and on the same color on two opposite sides thereof, as clearly 20 seen in Figure 2, where, for instance, the white suit has "K" and "9" marked on white ground on one of the dice shown at the left of the figure; while "A" and "J" are marked on white ground on the middle of the dice, 25 and "Q" and "10" also marked on white ground on the third of the dice, thus completing one suit.

Having thus described the invention, what is claimed as new is:

1. In a game comprising a set of three 30 dice, all having the same three ground markings, the opposite sides of each of the dice bearing the same ground marking, and one series of indices for each of said dice, all three dice having the identical series of indices, the same one of the indices occurring on a different ground marking on the different dice, thus spreading one series of indices on the same ground marking over all 35 three dice.

2. In a game comprising a set of three dice with opposite sides colored alike, the same three colors being used for all three dice, a series of indices of the same values marked on each of said dice, the sides of 40 each of the dice each carrying an index of a different value, the indices of the same value occurring on different colored sides on the three dice, thus representing suits in a card 45 game, each suit being distributed over all 50 of the dice in the set.

In testimony whereof I affix my signature.

JOHN B. SOUZA. [L.S.]
